UNITED STATES PATENT OFFICE.

MICHAEL FROSCHMAIER, OF BAD AIBLING, GERMANY.

PROCESS FOR PERMANENTLY REMOVING WALL-SALTPETER AND SIMILAR ERUPTIONS.

No. 847,173.

Specification of Letters Patent.

Patented March 12, 1907.

Application filed February 11, 1907. Serial No. 356,874.

To all whom it may concern:

Be it known that I, MICHAEL FROSCHMAIER, painter, a citizen of Germany, residing at Bad Aibling, Bavaria, Germany, have invented certain new and useful Improvements in Processes for Permanently Removing Wall-Saltpeter and Similar Eruptions; and I do hereby declare the following to be a full, clear, and exact description of the invention, such as will enable others skilled in the art to which it appertains to make and use the same.

The present invention relates to a process for permanently removing wall-saltpeter and similar eruptions.

The invention consists, essentially, in thoroughly heating the affected parts of the wall, for which purpose the ordinary plumbers' blow-lamps are especially suitable.

To permanently remove the wall-saltpeter, the affected part must first be cleansed of the coating of saltpeter by dry scraping or brushing and then subjected to the heat of the blow-lamp, beginning the application of the flame in the center of the spot and gradually working outward. The application of heat must be continued until small scales about one-half to one millimeter thick begin to come away from the wall, accompanied by a low crackling noise.

Experiments and trials have shown that the heat of the blow-lamp destroys all harmful elements in the wall to a depth of from two to three centimeters. After the burning of the wall a solution of potassium silicate and powdered carbonate of lime in water should be applied in advantageously two coatings in order to prevent with certainty a return of the evil. The object of these coatings is to prevent the entrance of moisture, the addition of carbonate of lime being made to prevent decomposition.

The appearance of the saltpeter spots is certainly not restored by this process; but

this may be remedied by giving the wall, advantageously one day after the burning, a coat of whitewash or paint. This coat will cure the unsightly appearance of the wall, and a return of the ugly wall-spots is prevented.

In the case of new buildings the walls may advantageously be first given the usual ground coating of distemper, and the saltpeter spots will then appear within a few days and be more easily distinguishable upon the painted surface.

What I claim as my invention, and desire to secure by Letters Patent, is—

1. The process which consists in applying heat to wall-saltpeter and similar eruptions until the surface scales off.

2. The process which consists in applying heat to wall-saltpeter and similar eruptions until the surface scales off and then applying thereto a waterproofing coating.

3. The process which consists in applying heat to wall-saltpeter and similar eruptions until the surface scales off and then applying thereto a water solution of potassium silicate and carbonate of lime.

4. The process which consists in applying heat to wall-saltpeter and similar eruptions until the surface scales off and then applying thereto a water solution of potassium silicate and finally painting.

5. The process which consists in progressively applying heat to wall-saltpeter and similar eruptions from the central portion to the outer boundary of the affected locality until the surface scales off with a crackling noise, then coating with a water solution of potassium silicate and carbonate of lime, and finally painting.

In testimony whereof I hereunto affix my signature in the presence of two witnesses.

MICHAEL FROSCHMAIER.

Witnesses:

ABRAHAM SCHLESINGER,
LOUIS F. MUELLER.
